UNITED STATES PATENT OFFICE.

GRANT SIPP, OF PATERSON, NEW JERSEY.

WARPING AND BEAMING MACHINE.

1,401,655.

Specification of Letters Patent. Patented Dec. 27, 1921.

Application filed April 9, 1917. Serial No. 160,627.

To all whom it may concern:

Be it known that I, GRANT SIPP, a citizen of the United States, residing at Paterson, in the county of Passaic and State of New Jersey, have invented certain new and useful Improvements in Warping and Beaming Machines, of which the following is a specification.

This invention relates to the beaming of warps or the like. The rotation of the reel in beaming machines is usually resisted by a brake strap to preserve a certain needed tension on the warp. Ordinarily the brake strap is held taut by a weight, the inertia of which, if it is heavy enough to maintain the required tension, is frequently responsible for breakage of the threads if the machine is suddenly started. My object is to avoid this, and I accomplish this object by employing an elastic element to resist the tendency of the brake-strap or equivalent to advance, as an incident of friction, with the reel. My invention further contemplates and makes possible more facile operations in obtaining adjustments of the braking resistance and finer degrees of adjustment of such resistance than are incidental to the use of weights. My invention further contemplates providing for an equalized braking resistance being applied to the reel at both sides thereof, so that the wear on the reel bearings will be equalized and the reel therefore kept always true.

Another object of the invention is to construct and arrange the brake strap or band so that, when the machine is adapted also for warping and (as sometimes is the case) no braking resistance is wanted, it may be shifted clear of the reel.

40 In the accompanying drawings,

Figure 1 shows a warping and beaming machine provided with the improved braking means;

Fig. 2 is plan of the frame of the machine and certain parts of the braking means;

Fig. 3 is a front elevation of the anchorage bracket for the fixed end of the brake-strap;

50 Fig. 4 is a fragmentary front elevation of the tension lever; and,

Fig. 5 shows an adjusting means.

a is the frame of a warping and beaming

machine of the so-called Swiss type, and *b* is the reel journaled in bearings *c* therein. 55 The reel, in warping, is driven in the usual manner by the friction wheel *d* shiftable by operating the treadle *e* into contact with the friction band *f* of the reel, said friction wheel being driven from the means *g* 60 at the beaming end of the machine by the sprocket-and-chain transmission *h*; in beaming the reel is driven by the pull of the warp as it winds on the beam *i*, which is rotated by the means *g*.

65 The brake strap *j* may consist, as is frequently the case, of a metallic strip lined with leather or the like; in the present case it is stiffened at one end by a strip *j'* for a reason to be explained.

70 As an anchorage means for one end of this strap I provide the elongated bracket or standard *k* which is pivoted to the frame at *l* on an axis parallel with that of the reel and projects up more or less close to the 75 periphery of the band *f* thereof; the metallic strip of the brake-strap has one end thereof suitably clamped to the bracket *k*. The bracket is provided with a lateral projection *m* which overhangs the upper surface of the frame, being equipped with a set screw *n* which may be made to bind 80 down against said surface to hold the bracket in such position that the brake-strap extends without distortion from the 85 bracket to the periphery of the band *f*.

86 In a bracket *o* on the top of the frame is arranged a short shaft *p* which affords at its ends a fulcrum for a U-shaped lever *q* having an arm *r* to which the free end of 90 the brake-strap is clamped by suitable means. In the construction herein actually shown the elements *f*, *j*, *k*, and *q*, with their accessories, are duplicated, there being one 95 set at each side of the reel—see Fig. 2, showing the parts *q* and *k* and their accessories duplicated.

100 Fulcrumed in each bracket *o*, preferably on shaft *p*, is a lever *s* depending well downwardly and having a threaded stud *t* projecting therefrom through an extension *q'* of the adjoining lever *q*. On each side of said extension there is arranged on said stud a nut *u*; by adjusting these nuts, leaving them clamping the extension of lever *q* 105 between them, the angular relation of the

levers q and s may be altered. The two levers s are connected at their lower ends by a bar y .

It will be seen that the levers q and s , with the bar y , constitute a lever structure having levers or lever parts (q and s) adjustable with reference to each other around their common fulcrum p in the brackets o .

The means for manually shifting this lever structure consists of a nut v which is journaled in a stand w and a rod x having a threaded end x' engaged with the threading of the nut, its other end being secured to the cross-bar y , connecting the lower ends 15 of the levers s , at about its mid-point; the nut may have a hand-wheel v' for turning it. A spring z tends normally to move the lever structure in the direction to release the brake-straps.

An important element of my invention, as already indicated, is the employment of elastic means to resist the tendency of the brake-straps or equivalent to advance, as an incident of their frictional grip on the reel, 20 with the latter. In the present instance the elasticity is present in the lever structure, and particularly the long bar y which, being held by the rod x at its center, is to a certain extent flexible and may yield at its 25 ends in response to the pull of the brake-straps on the arms r of levers q as an incident to their friction-grip on the rotating reel. If the machine is suddenly started up the stress on the warp threads is absorbed 30 by the lever structure; thus breakage of the warp threads, so common where the inertia of dead weights must be overcome on suddenly imposing a strain on the threads, is avoided.

By the described means for adjustably imposing a strain on the brake-straps the finest degrees of adjustment may be obtained by a simple and conveniently effected manipulation; adjustment may be effected 45 either by nut v or nuts u , or both, as conditions require. By duplicating the braking means and applying the braking resistance at both sides of the reel an equalized braking resistance is applied such as will avoid 50 torsion of the reel and keep it true to its bearings.

Where the machine is also adapted for warping it may in some cases be desired to allow the reel to rotate without braking resistance. In such a case, the nut v is turned to move the lever structure counter-clockwise, tending to elevate the brake-straps clear of the bands f . The strips j' give rigidity to the straps at this time as to their 55 end portions which are attached to the lever structure, which, taken with the fact that the brackets k extend well up to the reel bands f , insure the straps against falling to one side out of embracing relation to 60 the reel bands.

An important feature of my invention is the placing of the braking-pressure-adjusting element v' at the beam end of the machine, whereby the operator can set the tension to a nicety without leaving the position required for starting and stopping the beam driving means g , the usual controlling treadle for which is shown at 2, Fig. 1.

Having thus fully described my invention, what I claim as new and desire to secure by Letters Patent is:—

1. In a machine of the class described having a rotary member whose rotation is to be resisted, the combination of a supporting structure and mechanism therein to resist rotation of said member including a brake device to frictionally contact with said member and means to resist movement of said device with said member due to friction between them including a flexible elastic lever structure; said supporting structure having means to support said member with its axis parallel with the fulcrum of said lever structure.

2. In a machine of the class described having a rotary member whose rotation is to be resisted, said member having around its axis a pair of spaced braking surfaces, the combination of a supporting structure and mechanism therein to resist rotation of said member including a pair of brake devices to frictionally contact with said surfaces, and means to resist movement of said devices with said member due to friction between said devices and surfaces including a bar, spaced levers connected by and each having its axis parallel with said bar, means to connect said levers with said devices and means to connect the bar at a point therein between said levers with said supporting structure.

3. In a machine of the class described having a rotary member whose rotation is to be resisted, the combination of a supporting structure and mechanism therein to resist rotation of said member including a brake device to frictionally contact with said member and means to resist movement of said device with said member due to friction between them including a pair of levers arranged in said supporting structure and fulcrumed on a common axis, means to change the angularity of one of said levers with reference to the other, the brake device being connected with one lever, and means to connect the other lever with said supporting structure.

4. In combination, a supporting structure, a rotary member journaled therein, a brake-strap having braking contact with said member, an anchorage bracket for the brake-strap pivoted in said structure and projecting toward the periphery of said member and having one end of the strap attached to its free end portion, and means, attached 130

to the other end of the strap, for exerting tension on the latter.

5. In combination, a supporting structure, a rotary member journaled therein, a brake-
5 strap having braking contact with said member, an anchorage bracket for the brake-strap pivoted in said structure on an axis parallel with the axis of rotation of

said member and projecting toward the periphery of said member and having one end 10 of the strap attached to its free end portion, and means, attached to the other end of the strap, for exerting tension on the latter.

In testimony whereof I affix my signature.

GRANT SIPP.
